UNITED STATES PATENT OFFICE

136,077

DESIGN FOR AN EARRING

Michael Chernow, New York, N. Y.

Application May 5, 1943, Serial No. 110,126

Term of patent 7 years

To all whom it may concern:

Be it known that I, Michael Chernow, a citizen of the United States and residing at New York, in the county of New York and State of New York, have invented a new, original, and ornamental Design for an Earring, of which the following is a specification, reference being had to the accompanying drawing, forming part thereof, and in which

Fig. 1 is a front elevational view of an earring showing my new design,

Fig. 2 is a side elevational view thereof.

I claim:

The ornamental design for an earring, substantially as shown.

MICHAEL CHERNOW.
